UNITED STATES PATENT OFFICE.

WILLIAM H. PERRY, OF CONCORD, NEW HAMPSHIRE.

DESIGN FOR A MONUMENT.

SPECIFICATION forming part of Design No. 23,745, dated October 23, 1894.

Application filed September 26, 1894. Serial No. 524,204. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for a Monument, of which the following is a specification, reference being had to the accompanying drawing.

My design consists in the particular configuration of the shaft, its ornamental tablets, its cap piece, and the various styles of finish, all of which will be fully set forth in the following specification, and clearly illustrated in the accompanying drawing, on which reference letters and figures will be used.

The base 1, has four vertical sides which terminate at their top in an obtuse frustum of a pyramid 2, and upon this rests the pedestal which has four vertical sides 3, terminating at their top in an acute frustum of a pyramid 4, and on one or more sides of the latter is provided a raised tablet 5.

The shaft for the most part, has four tapering sides 6, each being ornamented with the polished tablets 7, distinguishable by heavy border lines of the configuration shown at 8. The shaft is further ornamented by the raised

tablets 9, having the top and bottom configuration shown respectively at 10 and 11,—the lower edge represented at 11, being beveled.

Above the tablets 9, is a four sided tapering portion, or acute frustum of a pyramid 12, each side of which is ornamented with a raised figure of "trefoil" design, 13, and above this frustum of a pyramid 12, is a cap piece consisting of the raised tablets 14, terminating in a pyramid 15; the lower edges of said tablets 14, being beveled as seen at 16, and the upper edges being notched as seen at 17.

The various styles of finish are designated by letters of reference,—A representing rock work, B hammered work, and C polished work.

Having described my new design, what I claim is—

The design for a monument, substantially as herein shown and described.

In testimony whereof I affix my signature in presence of two witnesses.

WILLIAM H. PERRY.
